UNITED STATES PATENT OFFICE.

ALBERT W. PEARSALL, OF NEW YORK, N. Y., ASSIGNOR TO THE METEOR DESPATCH COMPANY, OF BOSTON, MASSACHUSETTS.

VALVE FOR PNEUMATIC-DISPATCH-TUBE SYSTEMS.

SPECIFICATION forming part of Letters Patent No. 527,073, dated October 9, 1894.

Application filed April 16, 1894. Serial No. 507,675. (No model.)

To all whom it may concern.

Be it known that I, ALBERT W. PEARSALL, of New York, county of New York, and State of New York, have invented certain new and useful Improvements in Valves for Pneumatic-Dispatch-Tube Systems; and I do hereby declare that the following is a full, clear, and exact description of the invention, which will enable others skilled in the art to 10 which it appertains to make and use the same.

My invention relates to certain new and useful improvements in pressure valves for terminals in pneumatic dispatch tube systems in which pressure is used as a propelling medium for the carriers, and it consists of certain novel features, arrangements and combinations hereinafter described and particularly pointed out in the claims.

In the drawings:—Figure 1 represents a side view of the terminal with parts in section. Fig. 2 is a cross-sectional view taken on the line $z z$ of Fig. 1 and looking in the direction indicated by the arrow. Fig. 3 is an inverted plan view of the bottom of the terminal taken 25 on the line $x x$ of Fig. 1, looking in the direction indicated by the arrow. Fig. 4 is a detail perspective view of the pressure valve of the terminal.

In the drawings like letters of reference refer to like parts throughout the several views.

The terminal A consists of an outer curved guiding plate A' and the flat sides A², with an inner curved guiding plate A³, cast, or otherwise secured, to the sides A² of the terminal, or, if desired, it may be cast with or otherwise secured to the bottom plate of the terminal, and extending about one-half the distance of the outer curved guiding plate A'. At the upper end A⁵ of the curved plate A³ 35 the guide rods A⁴ are secured and also held in position by the braces A⁶ secured to the sides A² of the terminal. This construction permits the pressure, passing around the inner curved plate A³, to pass between and 40 around the rods A⁴ to the outlet or return tube E of the terminal.

The outer curved guiding plate A' and inner curved guiding plate A³, with the rods A⁴, are drawn on circles of different diameters so as to provide a sufficient space in the 45 upper part of the terminal, between the outer

plate A' and the inner plate A³ with its guide rods A⁴, to prevent the carrier being obstructed as it is driven through the terminal toward the discharge opening. The inlet 55 tube B, through which the carrier is driven to the terminal, is secured to the terminal A between the outer plate A' and the inner plate A³, so that the carrier, entering the terminal, passes up between the said two 60 plates and around between the outer plate A' and guide rods A⁴ to the valve C in the bottom of the terminal. The upper portion of the terminal is secured to the bottom plate D, and at one end of said plate the inlet tube 65 B and outlet or return tube E are secured. The opposite end of this plate is cut away, as indicated in Fig. 1, to provide an opening D', which extends from near the point where the tube E is secured to the bottom plate to the 70 point where the outer plate A' is secured to the plate D. This opening D' is closed by the valve C having its shaft C' journaled in the lugs C² formed in the sides of the plate D around the opening D', and the said valve 75 C is constructed of three leaves, C³, C⁴ and C⁵, the leaves C⁴ and C⁵ being of equal length from the shaft, while the leaf C³ is shorter than the said leaves C⁴ and C⁵. The valve is held in a horizontal position, as shown in 80 full lines, by the pressure of the air, which is greater on the right hand leaf C⁴ than on the left hand leaf C³, which pressure holds the two leaves C³ and C⁴ tightly to their seats and prevents the escape of air through the opening D', so that a continuous pressure is kept 85 up through the inlet tube B, terminal A and outlet tube E, as the pressure passes around the inner curved plate A³ and between the guide rods A⁴ to the outlet pipe E. The 90 pressure being equal and there being a greater area on the right hand leaf C⁴ it is held down tightly to its seat, and the left hand leaf C³ is held tightly up to its seat.

In the normal condition of the apparatus 95 when no carrier is received at the terminal a continuous current of pressure is kept up through the inlet tube B, terminal A and outlet tube E, and the pressure acting on the valve C holds said valve tightly to its seat, as above described, and prevents any escape of pressure through the opening D'.

For convenience we will assume that the drawings represent the terminal at the salesman's station, although it is equally well adapted to the cashier's station. A carrier being returned from the cashier, enters the terminal A through the inlet tube B, passes around the curve formed by the outer plate A' and inner plate A³ and guide rods A⁴, and strikes the leaf C³ of the valve C with sufficient momentum to overcome the pressure on the leaf C⁴ of the valve, which is of greater area, and thereby causes the valve C to revolve on its shaft C' and throws the leaves C³, C⁴ and C⁵ in the position shown in dotted lines to permit the discharge of the carrier. When the valve, by reason of the discharge of the carrier, has taken the position shown in dotted lines, the pressure, acting directly on the third leaf C⁵, forces it back to its normal position, shown in full lines, and consequently brings the other two leaves C³ and C⁴ back to their seats and horizontal position, as shown in the drawings.

A closed chamber F is provided, having the curved end piece F' and flat sides F², which, with the valve C⁵ in its normal position as shown in Fig. 1, form a closed air chamber, and the leaf C⁵ in moving upwardly in said chamber makes a close joint with the end and sides of the chamber, so that the pressure acting on the leaf C⁵, when the leaf is in position shown in dotted lines, cannot escape from the terminal by reason of the leaf C⁴ being raised, and the leaf C⁵ making a close fit with the end and sides of the chamber F, prevents any escape of pressure, which is thereby compelled to act upon the leaf C⁵ and force it down to its normal position, and the other two leaves C³ and C⁴ to their normal positions, all as hereinbefore described.

The valve C, as shown in Figs. 1 and 4, is a casting with the leaves slotted, and in the slots some suitable material as pure gum, sheet rubber, or raw hide, C⁶ is inserted with the edges of the substance projecting a sufficient distance all around from the casting to form the contact surfaces of the leaves of the valve C with their seats.

In the outlet tube E there is provided a branch tube G, the opening of which has a V valve G', the leaves of which are tightly held together by the internal pressure in the system. If the pressure is light and not sufficient to hold the leaves together, light springs may be provided to bear against the leaves to hold them closed, but usually the pressure is sufficient of itself to hold the leaves closed.

To send a carrier to the cashier it is pushed into the branch tube G, between the leaves of the valve G', and enters the return tube E by which it is driven to the cashier, and the leaves of the valve G' are closed by the pressure as soon as the carrier has been inserted, so there is no means of escape for the pressure.

As above stated the valve C, as described, is adapted for systems using pressure as a propelling medium for the carriers, in distinction from systems in which the propelling medium is a vacuum, that is, in which the air in front of the carrier is removed and the carrier is drawn by the suction in front of it and not driven by pressure behind it.

I do not limit myself to the exact arrangement and construction shown, as the same may be varied without departing from the spirit of my invention.

Having thus ascertained the nature and set forth the construction of my invention, what I claim as new, and desire to secure by Letters Patent of the United States, is—

1. In a pneumatic dispatch tube system, the combination, with a terminal having an opening for the discharge of carriers, of a valve normally closing said opening and held in its closed position by the pressure in the system.

2. In a pneumatic dispatch tube system, the combination with a terminal having an opening for the discharge of carriers, of a valve provided with leaves and pivoted in said opening, which is normally closed by two of the leaves of the valve of different areas.

3. In a pneumatic dispatch tube system, the combination with a terminal having an opening for the discharge of carriers, of a valve having connected surfaces of different areas exposed to the pressure of the system and normally closing said opening.

4. In a pneumatic dispatch tube system, the combination with a terminal having an opening for the discharge of carriers, of a valve normally closing said opening and provided with surfaces of different areas exposed to the pressure of the system and adapted to move in opposite directions when the valve is opened by the momentum of the carrier.

In testimony whereof I have signed my name to this specification, in the presence of two subscribing witnesses, on this 10th day of April, 1894.

ALBERT W. PEARSALL.

A. F. ACTON,
L. H. TROW.

Correction in Letters Patent No. 527,073.

It is hereby certified that the assignee in Letters Patent No. 527,073, granted October 9, 1894, upon the application of Albert W. Pearsall, of New York, N. Y., for an improvement in "Valves for Pneumatic Dispatch Tube Systems," should have been described and specified as the *Meteor Despatch Company, of Maine*, instead of the "Meteor Despatch Company, of Boston, Massachusetts"; and that the said Letters Patent should be read with this correction therein that the same may conform to the record of the case in the Patent Office.

Signed, countersigned, and sealed this 8th day of January, A. D. 1895.

[SEAL.]

JNO. M. REYNOLDS,
Assistant Secretary of the Interior.

Countersigned:

JOHN S. SEYMOUR,
Commissioner of Patents.
